UNITED STATES PATENT OFFICE.

THOMAS PATTON, OF CLEVELAND, OHIO.

PIPE-TONGS.

SPECIFICATION forming part of Letters Patent No. 278,264, dated May 22, 1883.

Application filed March 20, 1883. (No model.)

To all whom it may concern:

Be it known that I, THOMAS PATTON, of Cleveland, in the county of Cuyahoga and State of Ohio, have invented certain new and useful 5 Improvements in Pipe Tongs or Wrenches; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention has for its object to provide 15 an improved plumber's pipe tongs or wrench, for use in the trades, of such construction as to insure a ready and easy handling of pipes; and to this end it consists in providing the wrench with three gripping-bearings, made of three distinct parts, consisting of a movable jaw pivoted 20 between two stationary cams or jaws, which are provided with neck portions, the inner face of one portion being made with a projection extending its length and widening out from one end to the other to fit in a corresponding 25 recess in the other part, thus forming a dowel or groove-and-tongue joint, said parts, when put together, resembling a solid bifurcated cam, and being provided with screw-threads, where- 30 by the parts are fitted in a handle having a corresponding screw-threaded socket therefor; and it consists in other details of construction, which will be hereinafter pointed out.

In the drawings, Figure 1 is a perspective 35 view of my improved wrench, showing the manner in which it is made to grip a pipe. Fig. 2 is a perspective view of one part of the sectional stationary cam, showing the gradually-widening recess in the inner side of its neck portion and the manner of fitting the pivotal 40 swinging jaw between the two parts. Fig. 3 is a perspective view of the other part, showing the projection on the inner side of its neck portion. Fig. 4 is a view illustrating the socketed handle as being screw-threaded, and showing the neck of the separable cam fitted therein and as put together, forming a continuous screw-threaded neck.

Referring more particularly thereto, A repre- 45 sents the handle, which may consist of a solid

bar having a hollowed screw-threaded end for the reception of the screw-threaded neck A', formed by the joinder of the parts a b of the sectional stationary cam, or it may be a tubular piece screw-threaded at the end, or any obvious 50 form for the manipulation of the device. That part of the device termed the "stationary" jaw or cam B is made in two pieces, a b, as shown, and when fitted together by the projection on the inner face of one part fitting into a corresponding recess on the opposite face of the other part, forming a neck, the periphery of which is round and screw-threaded to fit in the handle, as before mentioned. These parts turn 55 at a right angle to the handle, and are rounded or curved on the top, and are also ratcheted or serrated. The end of the parts a b, forming the neck A', are each made thicker at the inner face of said neck portions, producing a flange or edge, c, on each of said parts, which 60 incline somewhat downward toward the forward end of the parts. These sections, when fitted together by the increased thickness at the neck, form a space between them sufficient 65 to pivot therein a movable jaw, C, as shown at 70 e, by a pin running therethrough provided with a nut at each end or any suitable means. Said movable jaw C curves or turns up at one end, which is serrated, said turned-up and serrated 75 end being adapted to fit around and bite into 80 and hold a pipe on the opposite side to which it is engaged by the stationary cam. This jaw has extended side cheeks, d, which are formed by the serrated portion of the jaw being made wider, so as to give a greater gripping-surface 85 and to coact with the gripping-surface of the two serrated ends of the stationary cam B. The cheeks d also, when the device is un-employed, act to hold the jaw in a position to more readily take hold, the cheeks resting 90 against the top edge of the parts a b, near their extremity, which is not serrated.

The advantages of my improvement will be apparent, as by my construction of pipe-tongs I obtain a device made in separable parts, 95 whereby three gripping-points are obtained.

I am aware that wrenches have been invented whereby a greater or less number of gripping-points are obtained; but by my construction these objects are attained in forming the parts 100

differently and in such manner that they can be replaced when they become worn and injured or one part deteriorate more rapidly than another; and I am aware that cam-heads of a 5 pipe-wrench have been formed integral with the handle thereof, but in mine these parts are separable.

Other advantages of my device will be obvious to the skilled mechanic, such as the easy 10 manner in which it can be manufactured, which I prefer to do in the ordinary drop-forging, so that it does away with the necessity of "slotting out," which is necessary in many instances, and thus lessens its cost.

15 Having thus described my invention, what I claim is—

1. In a pipe-wrench, the combination of the serrated parts *a b* of the cam-head with the handle, as described, said part *b* having the 20 projection adapted to fit in the part *a*, forming a neck, said parts being separable, as and in the manner described.
2. In a pipe-wrench, the combination of the rigid cam of two separable parts, forming a 25 continuous screw-threaded neck when put together, as described, and the socketed handle with the movable pivoted curved jaw, said jaw being serrated and formed with the side cheeks for holding it in position, as set forth.
3. In a pipe-wrench, the handle formed of either a hollow or solid bar, provided at one 30 end with a screw-threaded socket, in combina-

tion with the parts *a b*, joined and forming the screw-threaded neck, as described, and the curved movable jaw pivoted between them, 35 said parts being formed and connected, substantially as described.

4. The combination, in a pipe-wrench, of the side jaws or parts provided with tongue-and-grooved tapering joints and central serrated 40 piece, the former being adapted to fit a socketed handle, as set forth.

5. The combination, in a pipe-wrench, of the side jaws tongued and grooved together and increased in thickness to form a space between 45 the jaws, a central gripping-jaw pivoted and working in said space, which jaw is enlarged at its serrated end to keep it in place on the jaws and to counterbalance the pressure and gripping-surface on each side of a pipe, as set 50 forth.

6. A pipe-wrench consisting of the central pivoted jaw, the separable side portions of the cam, as described, and handle, the side portions being socketed in the handle, as an article of manufacture.

In testimony that I claim the foregoing as my own I hereunto affix my signature in presence of two witnesses.

THOMAS PATTON.
